UNITED STATES PATENT OFFICE.

GEORGE H. BABCOCK, OF PLAINFIELD, NEW JERSEY.

HIP-TILE FOR ROOFING.

SPECIFICATION forming part of Letters Patent No. 430,367, dated June 17, 1890.

Application filed November 23, 1889. Serial No. 331,316. (No model.)

To all whom it may concern:

Be it known that I, GEORGE H. BABCOCK, a citizen of the United States, residing at Plainfield, in the county of Union and State of New Jersey, have invented certain new and useful Improvements in Hip-Tiles for Roofing, of which the following is a specification, reference being had to the accompanying drawings, in which—

10 Figure 1 is a plan view looking in a direction perpendicular to the line of the hip of a roof, showing an assemblage of roof-tiles and hip-tiles thereon. Fig. 2 is a cross-section of Fig. 1 on the line $x x$. Fig. 3 is a diagram referring to the relation of the form of the tiles to the angles of the roof. Fig. 4 is an enlarged longitudinal section of Figs. 1 and 5 on the line $y y$ looking edgewise to the plane of one slope of the roof; Fig. 5, an end 20 view of a hip-tile and two supplemental tiles as they lie on the roof, drawn on a similar enlarged scale; Fig. 6, an inverted plan view of the hip-tile; Fig. 7, a side view, and Fig. 8 an end view, of the same. Fig. 9 is a plan view 25 of the supplemental tiles; Fig. 10, a side view, and Fig. 11 an end view, thereof.

My invention relates to roofing-tiles of clay or other material, and is applicable to tiles having a diamond shape, or approximately 30 so, being laid in quincunx order.

My said invention consists of a combination hip-tile which by its structure is rendered expansible or contractible to compensate for variations in the distances of the final 35 edges of the roof-tiles proper from the hip.

My improved hip-tile is composed of two side or supplemental tiles and a central tile or cover spanning them. Of these the supplemental tiles are adapted to interlock with 40 and form a uniform border to roof-tiles of varying contour, said border running at an angle to the lay of the roof-tiles substantially parallel with the hip.

The roofing-tiles $A A$, Fig. 1, represent one 45 species of design to which the invention is applicable, the outwardly-curved contours a of the supplemental tiles B , however, being equally adapted to fit roof-tiles having inwardly-curved or otherwise varied contours 50 at their upwardly-flanged portions.

The supplemental tiles B have a down-

wardly-turned flange i , whereby they interlock with the upwardly-turned flange j of the roof-tiles A , also a downwardly-turned flange k , forming a continuation of the flange i , and 55 an upwardly-turned flange l , whereby they interlock with similar supplemental tiles above and below. The downwardly-turned flange k is provided with an internal projection or return m , which engages with the terminus n of the flange l , so as to prevent the supplemental tile from falling away from its normal position, it being secured to the roof at the part E by nailing or otherwise. The part E extends downward to form a foot, (see 60 Fig. 4,) whereby one end of the supplemental tile rests on the roof at the necessary height to overlap the other tiles. The other end and side of the supplemental tile, bearing the continuous flange k i , fits the surfaces of 65 the tiles B and A , lying in a common plane, the surface whereof is made continuous by abutment of the edges at o , Fig. 1.

p is an upwardly-turned flange whereby the supplemental tile interlocks with the cover-tile C and renders the joint weather-proof. The flange p stands at an angle to the plane 75 of the tile B , so as to form a substantially vertical terminal flange to the roofing at each side of the hip when the tiles are laid. 80

The cover-tiles C , Figs. 6, 7, and 8, are of a form corresponding to a half-frustum of a cone, being of greater circumference at their lower than at their upper ends, so as to overlap. An upward flange c is provided at their 85 smaller end and a downward flange d at their larger end to interlock and form a continuous tight covering over the variable space D between the supplemental tiles. The combined thickness of the flanges l , k , c , and d , 90 Fig. 4, necessitates a considerable overlap of the tiles C below the tiles B , as seen in Fig. 1. In order to properly cover and fit the reveal of the supplemental tiles so overlapped, there are projections f provided at each terminus of the larger circumference of the tile C . 95

An internal flange g is provided at the upper end of the cover-tile to interlock with the upper ends of the terminal flanges p of the supplemental tiles and hold the cover-tiles 100 longitudinally in position. The edges g' of the internal flange g converge, as seen in Fig.

S, on lines parallel with the surfaces of the tiles B, having contact therewith at h, Fig. 9, allowing a movement of adjustment of the tiles B toward and from the hips.

- 5 As seen in Fig. 5, the edges bearing the upturned flanges *p* of the supplemental tiles clear the cover-tile C and have a considerable range of adjustment therein. Variations in the distances of the flanges *j* of the roof-tiles 10 from the center line of the hip are thereby compensated for to a limited extent. Furthermore, variations in the angle or pitch of the roof as related to a given form of tile are also compensated for, such variation causing 15 the diagonal line of flanges to lie unparallel with the line of the hip. For instance, referring to the diagram Fig. 3, *s t u x* represent a plan of a roof-tile of the character considered, and *v w* the angle of the roof. 20 Then when the length (or a half thereof *t v*) of the tile bears the proportion to the breadth (or a half thereof *v u*) corresponding to that of the hypotenuse *v w* (equal to *t v* in the diagram) of a right-angled triangle *u v w* to its 25 base *v u*, in which the altitude *u w* is proportioned to the base *v u*, as the altitude *u w* of the roof *v w* to its half-breadth *v u*, the diagonals of the tile will be parallel to the hips and valleys of the roof. In this case the side 30 tiles B will be all of one pattern for a given proportion of tile; but where a different proportion exists they will require to be made in series of sizes to fit the varying distances of the tiles A from the hip. However the adjustability of the visible portion of the side 35 tiles B as herein constructed greatly reduces the variety of sizes required.

Having thus fully described my invention, what I claim, and desire to secure by Letters 40 Patent, is—

1. In combination with roofing-tiles having upwardly-turned flanges on a part of their contour, a supplemental tile having a downwardly-turned flange, whereby it interlocks 45 the upwardly-turned flange of the roof-tile, and an upwardly-turned flange at one end and a downwardly-turned flange at the other end, whereby it interlocks similar supplemental

tiles above and below, forming a border at an angle to the lay of the roof-tiles, substantially as described. 50

2. In combination with roofing-tiles having upwardly-turned flanges on a part of their contour, a supplemental tile having a downwardly-turned flange, whereby it interlocks 55 the upwardly-turned flange of the roof-tile, an upwardly-turned flange at one end and a downwardly-turned flange at the other, and an upwardly-turned flange on the remaining side, whereby it interlocks with a cover-tile 60 spanning the hip, substantially as specified.

3. In combination with roofing-tiles having upwardly-turned flanges on a part of their contour, a supplemental tile having a downwardly-turned flange, whereby it interlocks 65 the upwardly-turned flange of the roof-tile, an upwardly-turned flange at one end and a downwardly-turned flange at the other, and a foot at one end, whereby it rests upon the roof-boards and may be nailed thereto, substantially as described. 70

4. In a supplemental tile substantially of the character described, a return of the downward flange on its lower end, in combination with the upward flange of the tile next below 75 and the perforated foot at the upper end, whereby the tile is held securely in place, substantially as specified.

5. A cover-tile for the hip of a roof of conical form and with an upward flange on the 80 smaller end and a downward flange at the larger end, whereby it overlaps and interlocks the similar adjacent tiles, forming a continuous and tight covering the whole length of the hip, substantially as shown. 85

6. In combination with roofing-tiles having upward flanges, a covering-tile for the hip substantially of the character described, having an internal flange, whereby it interlocks 90 with the upward flanges of the side tiles and is held in place longitudinally, substantially as specified.
